UNITED STATES PATENT OFFICE

148,259

DESIGN FOR A COMBINED BOOKKEEPING MACHINE AND STAND

Jan Streng, Mason, N. H., assignor to Remington
Rand Inc., Buffalo, N. Y., a corporation of Dela-
ware

Application August 10, 1946, Serial No. 132,426

Term of patent 14 years

(Cl. D64—11)

To all whom it may concern:

Be it known that I, Jan Streng, a citizen of the United States, residing in Mason, county of Hillsboro, and State of New Hampshire, have invented a new, original, and ornamental Design for a Combined Bookkeeping Machine and Stand, of which the following is a specification, reference being had to the accompanying drawings, forming part thereof.

Figure 1 is a perspective view of the bookkeeping machine showing the new design as viewed from the right hand side, and the bookkeeping machine stand in dot-dash lines;

Fig. 2 is a front elevational view of the bookkeeping machine and stand;

Fig. 3 is a right-hand side elevational view of Fig. 2;

Fig. 4 is a left-hand side elevational view of Fig. 2;

Fig. 5 is a rear elevational view of Fig. 2. The dominant feature of the invention resides in the bookkeeping machine illustrated in solid lines.

I claim:

The ornamental design for a combined bookkeeping machine and stand, substantially as shown and described.

JAN STRENG.
